UNITED STATES PATENT OFFICE.

GEORGE P. BOSWORTH, OF CENTRAL FALLS, RHODE ISLAND.

AUTOMATIC CIRCULAR-KNITTING MACHINE FOR PRODUCING SPLIT-FOOT HOSIERY.

1,154,169.

Specification of Letters Patent. Patented Sept. 21, 1915.

Application filed June 2, 1913. Serial No. 771,157.

To all whom it may concern:

Be it known that I, GEORGE P. BOSWORTH, a citizen of the United States, residing at Central Falls, in the county of Providence and State of Rhode Island, have invented certain new and useful Improvements in Automatic Circular-Knitting Machines for Producing Split-Foot Hosiery, of which the following is a specification.

10 The invention forming the subject of this application for U. S. Letters Patent relates to that class of automatic knitting machines for producing seamless hosiery, and it consists essentially in the novel features and 15 instrumentalities hereinafter set forth and claimed.

The invention is more especially devised to provide circular knitting machines with auxiliary means for automatically producing 20 the finer grades of seamless hosiery having "high-spliced" heels and "split-foot" portions. Or, in other words, the machine is normally adapted to automatically produce seamless stockings having the usual 25 characteristics, as to the leg, heel, foot and toe portions; and through the medium of auxiliary devices connected to and coöperable with the machine, the latter is adapted to be readily converted into a knitting 30 machine for producing split-foot stockings, so-called, wherein the respective threads of the web comprising the top and bottom portions of the foot part of the stocking are caused to interlock and form two parallel lines of 35 juncture stitches, one on each side thereof.

One object of the invention is to provide simple, efficient and comparatively inexpensive means adapted for knitting stockings of the split-foot class. To that end I employ 40 an independently movable secondary cam-block carrying guard-cams, a pair of stitch-cams and a pair of auxiliary picks, the latter being actuated by certain of the cylinder's needles in forming the said juncture lines of stitches when the machine is being 45 actuated in a reciprocatory manner; the said cam-block is located substantially diametrically opposite the usual main knitting-cams.

50 A further object of the invention relates to means for automatically moving said cam-block and its members toward and from the needle-carrying cylinder at predetermined points, whereby the machine is adapted 55 to produce regular circular courses of

stitches or plain knitting, as well as freely permitting the formation of the heel and toe portions. That is, the usual narrowing and widening picks are normally operable while the cylinder is being reciprocated in knitting 60 the heel and toe.

A further feature of the invention resides in automatically controlled stitch-forming means and mechanism for reciprocating the needle cylinder, whereby, in producing 65 the split-foot part of the stocking, the oppositely disposed groups of long and short-butts needles are respectively caused to simultaneously knit the corresponding threads to form partial rows of plain or 70 ordinary stitches on the respective sides of the foot part, and means constructed and arranged by which a pair of medium-butts needles, located respectively between the ends of the two groups of long and short 75 butts needles, are caused to receive both the said threads on each medium-butts needle and interlock them with the threads on both sides of the foot part during each double-reciprocation of the needle-cylinder. 80

The improvements constituting the present invention are shown in connection with a full automatic circular knitting machine in which the needle-carrying cylinder is revoluble, and the corresponding stitch-cams 85 relatively stationary. The machine as a whole, except as to the present improvements, and forming the subject of this application for patent, is substantially the same as disclosed in J. D. Hemphill's Patent 90 No. 933,443, of Sept. 7, 1909, to which patent reference may be made. It may be stated, however, that in the present instance, one-half of the total number of needles in the needle-cylinder may have long-butts, the 95 other or opposite half of the needle-row having short-butts, except that two of the latter needles (one at each end of the semi-circular row) is provided with slightly longer butts, which may be termed medium-butts 100 or suture needles. These latter are employed in connection with the other needles and coöperating devices in producing plain or ordinary knitting. The medium-butts needles are also used in making the said 105 lines of juncture stitches which join or connect the adjacent parts of the web when stockings having high-splice and split-foot portions are being produced.

In the accompanying four sheets of draw- 110

ings. Figure 1 represents a partial elevation of the left side of a knitting machine provided with my improvements, the latter being positioned to produce the split-foot part 5 of a stocking; Fig. 2 is a corresponding vertical section, enlarged, taken substantially on line $o-o$ of Fig. 4, portions not shown; Fig. 3 is a partial elevation, viewed from the back of the machine, showing details of the 10 connections; Fig. 4 is a top plan view; Fig. 5 is a perspective view showing the improved secondary cam-block; Fig. 6 is a side elevation of the cam-block showing its inner face; Fig. 7 is a corresponding top plan view, portions being omitted; Fig. 8 is a detail perspective view of one of the swinging auxiliary picks; Fig. 9 is a partial horizontal sectional view, taken substantially on line $2-2$ of Fig. 2, parts being omitted; Fig. 10 is a horizontal sectional view, taken 15 on the irregular line 10—10 of Fig. 11, showing the secondary cam-block in the outward position; Fig. 11 is a vertical section, similar to Fig. 2, but showing the relation of 20 said cam-block, etc., to the cylinder when plain circular knitting is being produced; Fig. 12 indicates a plan view of the needle-cylinder, partly in horizontal section, showing the relation of the needles with respect 25 to the center line A, A' , Fig. 4, at the commencement of a rotary reciprocating movement; Fig. 13 is a corresponding development of the cylinder's outer periphery, indicating its needles, and the relative position 30 of the latter to the stitch-cams, etc., at that instant; Fig. 14 represents the relation of the needles to the center line at the end of the first semi-revolution; Fig. 15 indicates the corresponding development showing 35 the relative positions of the needles to the stitch-cams; and Fig. 16 indicates the cylinder at the completion of the full revolution.

The following is a description of some of 45 the parts embodied in the patented automatic circular knitting machine before referred to, and in which machine my improvements are well adapted to be combined and successfully employed:

50 In the drawings herewith C designates a portion of the main frame having a base member a secured to its top end for supporting the revolvably-driven needle-cylinder D and other co-operating instrumentalities. A 55 flat cam-plate b , capable of slight vertical movements, has the cylinder D freely revoluble therein; the upper face of the plate is provided with an annular needle-support or ring-cam M having its inner face contiguous 60 to the periphery of the cylinder. The cylinder is surmounted by a normally stationary pivoted carrier-ring b' provided with yarn levers, etc., for feeding threads to knitting devices, substantially as usual. A main cam-block B is positioned on the plate b , the said 65

ring-cam M being cut away on that side (right) of the machine to receive it; the block is provided with oppositely located main knitting-cams v^3, v^4 , the corresponding narrowing or needle-elevating picks v, v^1 , 70 and center guard-cam v^5 , substantially as indicated in Fig. 15. When the knitting cylinder is caused to move in a rotary-reciprocating manner, as in knitting the heel and toe parts of a stocking, the upper or "draw" 75 member i^2 and the lower or "raise" member i^3 of the guided instep-cam are first moved upward to temporarily position all the long-butt needles i idly in the upper path or plane, the latter then being in alinement 80 with the guiding groove i^5 of the instep-cam, substantially as represented in the said Hemphill Patent #933,443—see also Fig. 15. Means are provided for controlling the action of the automatically positioned 85 widening or needle-depressing picks w, w^1 in producing the said heel and toe portions, substantially as set forth in said patent; that is, a recessed cam g indicated by dotted lines, 90 Fig. 1, secured to the main cam or pattern-shaft s^2 (which latter is caused to revolve once only during the production of each stocking) is engaged by a pivotally mounted lever g^1 jointed to a vertical connection g^2 , in turn jointed to a pivoted bent horizontal 95 lever having its free end g^3 supporting a vertically mounted pin g^4 adjustably secured to a member having a stop plate g^5 fixed to its inner end. When the stop is in the elevated position the picks w, w^1 , are 100 adapted to be alternately engaged by a pair of short butt needles from the corresponding end of the column of idle needles and deflected downward to the knitting path during each reciprocating movement of the cylinder. 105

B^1 indicates the improved secondary cam-block as a whole, slidably mounted on the cam-plate b . It comprises a frame or body part c^8 having oppositely inclined lateral sides on which latter are secured right and left stitch-cams u^3, u^4 extending above the line M^1 (Fig. 6) in alinement with the upper edge of the annular needle-support M. The inner faces of these last-named stitch-cams are depressed or recessed to permit the butts of the short-butt and medium butt needles to pass freely and idly in the lower plane between the adjacent faces of the cylinder and said stitch cams when the cam-block is inward, but are adapted to be engaged by the long butt needles i . A center raise cam u^2 and upper center guard cam u^2 are also secured to block B^1 and just clear the cylinder when the block is positioned inward. Right and left upper wing or guard cams c^2, c^1 are fixed to the respective arms of a member c , secured to the frame c^8 of the block B^1 . The inner faces of said parts u^2, u^1, c^1 and c^2 are disposed in a circular plane common 110 115 120 125 130

to all. A pair of oppositely facing needle-elevating auxiliary picks u, u^1 , having pivot pins u^6 , are mounted to swing on the inclined sides u^9 of the stitch-cams; the inner free ends of these picks extend beyond the corresponding faces of the last-named stitch-cams and are adapted to receive the butts of the pilot or medium-butt needles m^1, m^2 only and temporarily deflect the latter, with their respective loops, to the upper idle plane at certain intervals, thereby permitting the immediately following long-butt needles to be readily guided to and under the other stitch-cam; the subsequent knitting action being effected in a well-known way. The outer ends of the auxiliary picks are connected by a light tension spring u^8 , the function of the spring being to return the picks to the normal seated position on the respective stitch-cams. In case the long-butt needles are in knitting action, the corresponding pick is arrested in its return movement and yieldingly supported by the butts while the latter are passing thereunder.

The following is a description of means for moving the cam-block B^1 : To the cam or pattern shaft s^2 , which is adapted to revolve in a step-by-step manner, is fixed a disk-like member F having its periphery provided with a short cam-lug n ; when the free end of the pivoted lever e rests upon the lug, as indicated in Fig. 1, the position of the cam-block is inward, thereby, in connection with other co-operative devices adapting the machine to produce the split-foot part of the stocking. To the rear end of the said pivoted cam-actuated lever e is connected a vertical link e^1 , in turn connected at its upper end by a short link e^4 to a pivoted bell-crank member e^6 , which in turn is jointed to a horizontal connection e^8 ; the opposite end of the latter being connected to an arm e^7 of a lever pivotally mounted on a bracket e^8 ; the opposite arm portion e^9 of the last-named lever being engaged by a pin e^{10} fixed in the outer end of a U-shaped member e^{11} secured to the base of the block B^1 . See Figs. 1, 3, 4 and 5. Upon the engagement of lever e with the outer periphery of cam F the block B^1 is thereby caused to move outward, thus forming a space between the inner faces of its several cams and the needle-cylinder for the free passage of the butts of all the needles. The cam-block B^1 is positioned outward while plain circular knitting and the heel and toe portions of the stocking are being produced. Figs. 10 and 11 represent the cam-block B^1 in the outward or temporarily inoperative position.

As before stated, the needle-cylinder is moving in a rotary-reciprocatory manner while knitting the high-splice heel and toe and split-foot portions of the stocking. In adapting the machine for high-splicing, the

said disk-cam F is provided with a detachably secured cam-lug n^1 , the latter being positioned thereon in advance of the companion lug n . This lug n^1 , in connection with the means just described causes the block B^1 to remain in the inward position while the lever e is in engagement with the lug. In case high-splice knitting is not desired, the lug n^1 is omitted. The removal of both lugs n, n^1 from disk F causes the secondary cam-block to remain idle in the outward position, the corresponding foot part of the stocking then consisting of continuous courses of plain rotary knitting. The heel and toe portions, however, being produced substantially as usual while the cylinder is reciprocating.

In connection with the mechanism for actuating the cam-block B^1 , the primary driving member F , with its lug n and co-operating lever e are also employed for positioning a secondary thread and secondary sinker-cam devices for normal knitting action simultaneously with moving said cam-block inward for normal action, the said devices being moved back to the inoperative position simultaneously with the corresponding movement outward of the cam-block. That is, the upper end of the link e^1 is also jointed to a pivoted bent horizontal lever e^2 having its forward free end e^3 supporting a spring-pressed vertical rod f mounted in a bracket f^1 secured to the stationary top plate a . The upper portion of the rod f is bent inward at an angle and terminates in a wedge-shaped end f^3 in engagement with a horizontal slidable member carrying the sinker-actuating cam k , the latter positioned to engage the sinkers k^1 ; the function and construction of the said cam and sinkers being substantially as indicated in J. Lawson's Patent No. 1,045,570 of Nov. 26, 1912. Fixed to said rod f is an upwardly extending member f^2 having a pin f^4 engaging a yarn-changer h movably mounted in a bracket h^1 secured to the carrier-ring b^1 for feeding the secondary thread to the stitch-cams, etc., of the cam-block B^1 , substantially as represented in Figs. 2 and 11; the latter figure showing the sinkers and thread in the idle or non-knitting position. I make no claim herewith broadly to said sinker-operating and thread-changing devices.

The action of the "throw-down" widening or needle-deflecting picks, w, w^1 is substantially the same as in the Hemphill machine herein referred to. That is, in knitting the heel and toe all the long-butt needles are idle in the upper needle-path. The narrowing picks v, v^1 elevate a short-butt needle alternately from each end of the column of short-butt needles, during each double reciprocation of the cylinder. At the end of the narrowing process the cam g , acting through intermediate mechanism, positions

the stop-plate g^5 upward, the said spring-pressed widening-picks at the same time moving upward also and positioning themselves in the upper needle path. A pair of short-butt needles from the forward end of the column of idle needles engage the corresponding widening pick and are depressed to the lower path; the foremost needle of the pair engages the adjacent narrowing pick and is elevated back to the idle column again, the other needle of the pair passes under the last-named pick to engage the corresponding stitch-cam, thereby casting its loop and increasing the width of the pocket. The operation being continued alternately from each side or end of the column of upper idle needles until the widening is completed.

In Fig. 9 of the drawings is represented a self-dropping pivoted swinging guide or latch member E arranged to be engaged by the butts of the column of long-butt needles to automatically deflect the said needles to the upper or idle plane, as in reciprocatory knitting, when the needle-cylinder is moving in one direction; the butts passing under the latch when the cylinder is turning in the opposite direction.

The following is a description of the manner of operation of a circular knitting machine provided with my improvements, when employed in automatically producing the split-foot portion (intermediate the heel and toe) of a stocking, the main and secondary cam-blocks, B , B^1 , with their several needle-controlling members, being in the normal inward position, and at the same time having the needle-carrying knitting-cylinder moving in a rotary-reciprocatory manner: In order to more clearly trace the action of the needles, it is assumed that a white thread is introduced above the main cam-block B and converted into stitches by its knitting-cams and the short-butt needles s (carrying white loops), a black thread being similarly and simultaneously acted upon by the knitting-cams u^3 , u^4 and the long-butt needles i (carrying black loops) in passing cam-block B^1 ; the latter being located diametrically opposite the main cam-block. As thus arranged, the needles s knit the white thread and produce the lower or sole part of the foot portion, while the needles i act upon the black thread and produce the upper part or half. In Figs. 13 and 15, indicating the development of the cylinder and cams, M denotes the cam-ring, its upper edge constituting the normal lower path for supporting the short-butt needles s . D^1 indicates the upper edge or nose of the cylinder D . B^x and W^x designate the respective knitting-sections in which the black and white portions of the foot are produced, and i^1 and s^1 are lines indicating the upper end of the column of long and short-butt needles,

respectively, or the "needle-wave" lines. Assuming the needle-cylinder D , Fig. 12, to have temporarily stopped at the end of a reciprocatory movement on the center line A^1 , A , the needles i then constituting a semi-circular row in one-half the cylinder and the needles s , m^2 , m^1 forming a semi-circular row in the opposite half, the corresponding relation of all the needles to the cam-blocks, etc., at that instant is substantially as represented in Fig. 13, which indicates a development of the cylinder's outer surface, the short and medium-butt needles then being in the lower idle needle-path shown in the left half of Fig. 13, the long-butt needles i at the same time being in the upper idle path, as shown in the right half of the same figure. Now, upon rotating the cylinder in the arrow or clockwise direction (see Figs. 12 and 13), starting, say from the point A^1 on the center line, the butts of the needles s (carrying white loops) pass freely in groove i^4 of the then elevated lower instep-cam i^3 and between the recessed faces of the stitch-cams u^4 , u^3 and the needle-cylinder, followed by the suture needle m^2 (carrying a black loop), said needle, by reason of its longer butt, engages auxiliary pick u^1 and is thereby deflected upward past knitting-cam u^3 without casting its loop, the said needle meanwhile receiving a semi-loop of black thread. The rotary movement of the cylinder causes the needle m^2 to engage the cam c^2 and deflect it (the needle) back to the lower path; i.e., upper edge of ring-cam M . The column of elevated idle long-butt needles i , immediately following needle m^2 , enters the open groove i^5 of the instep-cam and are guided downward by guard-cam c^1 to move between the still raised pick u^1 , cam u^4 and guard-cam u^2 , the latter cam deflecting the needles i to successively engage the knitting-cam u^3 , thereby casting the old black loops from the needles i into the black portion of the web and at the same time taking in new black loops. The needles i are guided back to the upper inactive plane by means of the notched ring-cam M and the pivoted guard or latch E . It is to be noted that the clearance or space formed between the adjacent faces of the latch E and needle-cylinder exceeds the length of the butts of needles s , m^1 and m^2 ; therefore the said needles are capable of moving idly circumferentially past the latch, but the butts of the needles i , being longer, extend across said space to engage the latch and ride upon it, thus guiding the needles i back to the upper idle plane. While the just described movements of said needles i are taking place the other needles s of the cylinder are also in simultaneous action on the opposite or right side of the machine. That is to say, the medium needle m^1 , starting at center point A in lower plane with

one white loop thereon, and following the idle elevated needles i , first engages the seated regular needle-elevating narrowing pick v^1 and is deflected to the upper plane 5 above the center guard-cam v^5 , at the same time retaining its loop and receiving a semi-loop of white thread; the immediately following needles s successively pass between said raised pick and knitting-cam v^4 of main 10 cam-block B, and engage the cam v^5 and are deflected under the companion knitting-cam in v^3 , the needles s at the same time taking in new white thread and casting off the old white loops into the white portion of the 15 web. Meanwhile needle m^1 continues moving in the upper plane (v^6) and at the end of the first semi-revolution is still elevated with one and one-half white loops thereon, its position then being at A¹. Figs. 14 and 20 15 indicate the corresponding positions of all the needles at the termination of the first semi-revolution of the cylinder. In making the second half of the first complete revolution in the said arrow direction from the 25 position indicated in Fig. 14 the then elevated needle m^1 , at A¹, in following the still raised pick u^1 and engages the center cam u^2 which latter deflects the needle under knitting-cam u^3 of block B¹, thereby 30 causing needle m^1 to receive a black thread in its hook and at the same time to cast off its two white loops over the new black loop into the web in producing the juncture line of stitches connecting the upper and lower portions of the foot part on that side of 35 the web; after thus casting its stitches said needle m^1 is guided upward by the inclined recess of cam ring M to the normal knitting level and moves freely past said guide E to the end of the revolution; the needle then 40 arriving at its starting point A again in the lower plane, but carrying a black loop only. At the same time the other medium-butt needle m^2 , immediately following the column of short-butt knitting needles s , in 45 moving from A to its original starting point A¹ is deflected by the still elevated pick v^1 to the center cam v^5 and from the latter to the stitch-cam v^3 of block B, and thence via 50 incline recess in cam ring M to the lower knitting plane, the needle m^2 meanwhile receiving a loop of white thread and casting its two black loops over the new white loop into the web in the formation of the corresponding juncture line of stitches, the latter 55 being diametrically opposite the other said juncture line; the needle m^2 continues moving in the lower plane to the end of the revolution, or starting point A¹; said needle then having thereon a loop of white thread; 60 the relative position of the cylinder and its 65 needles again being substantially as shown in Figs. 12 and 16, and completing one revolution of the double rotation of the cylinder. In rotating the cylinder in a contrariwise direction to that indicated in Figs. 12 to 70 16, inclusive, to complete its double reciprocation, the sequence of operations is practically the same as previously described, except that they are performed in a reverse order. In thus producing the split-foot part 75 of the stocking it will be observed that the reciprocation of the cylinder in the said arrow-direction causes the long-butt needles i to engage cam u^3 and knit only the black thread, the movement of the cylinder at the 80 same time causing the short-butt needles s to engage the diametrically opposite cam v^3 and knit only the white thread. The cylinder, when moving in the reverse direction, also causes needles i , in connection with cam 85 u^4 , to knit the black thread; the opposite set or group of needles s acting in co-operation with cam v^4 to knit only the white thread. Each of the medium-butt needles m^2 , m^1 , however, receives both threads and 90 also engages the two sets of stitch-cams, u^3 , v^3 and u^4 , v^4 , during each double reciprocation and causes the loops carried by said medium-butt needles to be cast therefrom and interlock with the end loops of the respective 95 black and white sections to produce the juncture lines of stitches at opposite sides of the foot.

The pick v and stitch-cam v^3 of cam-block B are disposed directly opposite the auxiliary pick u^1 and stitch-cam u^4 of the secondary cam-block B¹, and in front of a median-line $y-y$ (Fig. 4) extending longitudinally of the machine through the center of the needle-cylinder, and having the pick v^1 and 100 stitch-cam v^4 of the block B positioned directly opposite auxiliary pick u and stitch-cam u^3 of the block B¹ and at the rear of 105 said median line.

In an automatic knitting machine provided with my improvements, the secondary cam-block B¹ and the parts connected to and movable bodily with it are only capable of co-operating with the stitch-cams, &c., of the main block B to produce the split-foot part of the stocking when the block B¹ 110 is positioned inward, contiguous to the outer face of the revoluble needle-carrying cylinder, the latter then moving in a rotary-reciprocating manner. The block B¹ is in 115 the outward idle position while the heel and toe portion are being formed, and also while the machine is producing plain circular courses of stitches or "round-and-round" knitting. It may be stated further 120 that the said auxiliary picks, u , u^1 , are adapted to be engaged and actuated only by the medium-butt or suture needles, m^1 , m^2 ; these needles, respectively, constitute 125 alternately the forward or pilot needle of 130

the column of succeeding needles, according to the direction of cylinder rotation. By means of the engagement of the advance medium butt needle with the corresponding auxiliary pick the latter is caused to deflect the needle to the upper plane without casting its loops, thereby temporarily uncovering the lower needle path for the passage of the immediately following long-butt needles 15 *i*, thereby causing the latter to engage the corresponding stitch-cam and cast their loops into the web.

An automatic hosiery knitting machine of the general type referred to and equipped 15 with the herein described improvements is capable of making "high-splice" and "split-foot" knitting with increased efficiency; that is, the rate of output of first-class work produced is materially greater; the loss, due 20 to waste, is decreased; the wear upon the threads is practically *nil*, especially when silk, lisle, or tender threads are used, during the reciprocatory movements of the cylinder while the machine is knitting the 25 "high-splice" and "split-foot" portions of the stocking; and the medium butt needles are actuated or deflected with greater ease, in that they are subjected to less friction and strain, while at the same time these last 30 named needles are not liable to become accidentally overloaded with thread loops.

In the present improved machine, when actuated to produce split-foot knitting, the medium butt needles engage all the picks 35 to temporarily elevate them (needles m^1 , m^2) idly above and past the contiguous stitch-cams during each double-reciprocation of the cylinder and are also caused to engage all the said stitch-cams and cast their 40 loops into and interlock them with the adjacent plain end stitches in producing in the web two parallel lines of juncture stitches, one on each side of the foot part of the stocking. In other words, when the needle- 45 cylinder is operated in a rotary-reciprocatory manner so as to produce in the stocking high-splice and split-foot knitting the said suture or medium butt needles m^2 , m^1 are caused to simultaneously cast their loops 50 into the fabric in coöperation with the respective knitting cams v^3 and u^3 , during a complete revolution in one direction; and the said needles m^2 , m^1 , are adapted to cast other loops into the fabric in coöperation 55 with the respective knitting cams u^4 and v^4 in making the immediately succeeding revolution in the reverse direction; the above described action being successively repeated in the production of the respective courses of 60 such reciprocatory knitting.

What I claim and desire to secure by United States Letters Patent, is:—

1. In an automatic circular knitting machine, the combination of a needle-cylinder 65 provided with a plurality of suitably ar-

ranged series of needles, including the medium or suture needles, a pair of main stitch-cams, a pair of main needle-elevating picks disposed above the main stitch-cams, a pair of secondary stitch-cams disposed opposite 70 said main stitch-cams, a pair of auxiliary picks for elevating the suture needles only, said picks mounted for movement above the secondary stitch-cams, needle-deflecting guard cams, and means for automatically 75 positioning said secondary stitch-cams, auxiliary picks and guard cams for action, whereby, in coöperation with the needle-cylinder moving in a rotary-reciprocatory manner, as in split-foot knitting, the suture needles are caused to be alternately engaged by 80 the auxiliary picks and raised above and past the secondary stitch-cams without knitting and then deflected by the guard cams to the lower path to engage the corresponding 85 main stitch-cam on the other side of the machine and knit.

2. In an automatic circular knitting machine, the combination with a needle-cylinder provided with a substantially semi-circular row of long-butt needles, a similarly arranged opposite row of short-butt needles, and medium butt or suture needles mounted between the end needles of said rows respectively, of a pair of mounted main stitch 90 cams, a swinging, needle-elevating main pick located over each of said main stitch-cams, a pair of secondary stitch-cams for knitting engagement with the long-butt needles only, the last-named cams capable of being moved 100 in and out relatively to the needle-cylinder, a pair of swinging needle-elevating auxiliary picks for the suture needles, said picks being located over the respective secondary 105 stitch-cams and movable bodily with them, a pair of needle-depressing or widening picks located with relation to the auxiliary picks, a pair of spaced apart needle-deflecting guard-cams, and means for automatically placing said secondary stitch and 110 guard cams and auxiliary picks in the knitting and non-knitting positions at prearranged points in the cycle of operations.

3. In an automatic circular knitting machine having a needle-cylinder provided with suitably arranged long, short and medium-butt or suture needles, the combination therewith of diametrically opposed sets of main and secondary stitch-cams, main and auxiliary picks for the main and secondary stitch-cams, respectively, said picks constructed and arranged to elevate the said medium-butt needles only while the cylinder 120 is reciprocating in producing the high-splice and split-foot portions of a stocking, needle-deflecting guard cams, and means for automatically placing said secondary stitch and guard cams and auxiliary picks in knitting 125 position.

4. In an automatic circular knitting ma- 130

chine having a needle-cylinder provided with suitably arranged long, short and medium-butt or suture needles, the combination therewith of diametrically opposed sets of main and secondary stitch-cams, main and auxiliary picks for the main and secondary stitch-cams, respectively, said set of auxiliary picks constructed and arranged to raise only each medium butt needle, according to the direction of rotation of the cylinder, without casting the loop or loops therefrom, and secondary guard-cams adapted to deflect said medium-butt needle back to the lower plane so as to knit its loops into the web upon the needle's engagement with the corresponding main stitch-cam.

5. In an automatic circular knitting machine having a needle-cylinder provided with long, short and medium butt needles, and a main cam-block having a pair of main stitch-cams and a needle-deflecting main pick mounted over each stitch-cam, the combination therewith of a secondary cam-block, a pair of laterally spaced stitch-cams fixed to the latter block, each of said secondary stitch-cams having its inner face grooved or recessed for the free passage of the butts of the short-butt needles, a spring-pressed auxiliary pick extending into the needle-path and located over each of the respective stitch-cams to be engaged and actuated only by the medium-butt needles to elevate the latter without knitting, a pair of laterally spaced guard cams positioned on the secondary cam-block, adapted to deflect the elevated medium butt needles back to the lower needle-path, said needle in its movement being caused to engage one of the said main stitch-cams on the opposite side of the machine and knit its loops into the web at the juncture line thereof.

6. In a full automatic circular knitting machine, the combination of a needle cylinder provided with oppositely arranged, substantially semi-circular groups of long-butt and short-butt needles, respectively, medium-butt needles interposed between the ends of the two groups of needles, a main cam-block provided with stitch-cams and needle-elevating picks, a movable second cam-block, disposed diametrically opposite the said main cam-block, provided with stitch and guard cams, a pair of auxiliary needle-elevating picks actuated by the said medium-butt needles only, said auxiliary picks being mounted on and movable bodily with the cam-block, independently controlled means for feeding main and secondary knitting threads to the needles while the cylinder is reciprocating to produce "high-splicing" and "split-foot" knitting, means for moving the said second cam-block and its members inward toward the cylinder preliminary to knitting the split-foot portion of the stocking, and means for moving the cam-

block outward to render its members temporarily inoperative during the knitting of the heel and toe parts of the stocking.

7. In an automatic circular knitting machine having a needle-cylinder, means for actuating it in a rotary-reciprocatory manner, said cylinder provided with long, medium and short-butt needles, and instrumentalities, including main stitch-cams, needle-elevating and needle-depressing picks, constructed, arranged and adapted for co-operation, substantially as usual for producing plain seamless stockings, the combination therewith of a secondary cam-block provided with reversely arranged pairs of guard-cams, stitch-cams and auxiliary picks, said auxiliary picks adapted to elevate the medium butt needles, means for moving said cam-block inward, whereby in producing the split-foot portion of a stocking certain of the needles are caused to knit the lower part of the foot through the medium of said main stitch-cams, while at the same time members of the said secondary cam-block are caused to actuate other needles of the cylinder to knit the upper part of the foot and interlock the stitches at opposite sides of the web.

8. In an automatic circular knitting machine of the general character described, having a needle-cylinder provided with suitably arranged long, medium and short butt needles, and means for actuating the cylinder in a rotary reciprocatory manner, the combination therewith of knitting devices for causing certain of the needles to knit one part of the split-foot portion of a stocking, a secondary cam-block having knitting devices mounted thereon for knitting the other part of the split-foot portion, means for moving said secondary cam-block inward toward the cylinder to operatively position its members in producing said split-foot portion, and a pair of independently movable auxiliary picks pivoted to the secondary cam-block arranged to be engaged by the medium-butt needles in forming an interlocking juncture line of stitches on each side of the foot part.

9. In a full automatic circular stocking knitting machine having a revoluble cylinder provided with long, medium and short butt latch-needles, means for feeding a thread to be acted upon by all the needles and converting it into continuous courses of normal rotary knitting, and means substantially as usual, including needle-elevating and needle-depressing picks, for knitting the heel and toe portions of the stocking while the needle-cylinder is moving in a rotary-reciprocatory manner, the combination therewith of means for producing in the stocking high-splice and split-foot knitted portions while the cylinder is being actuated in a rotary reciprocatory manner, said high-splice and split-foot knitting means including an inwardly positioned

- movable secondary cam-block having a pair of recessed stitch-cams, a swinging auxiliary pick mounted above each stitch-cam for elevating the medium butt needles, center and 5 outer guard cams secured to and movable bodily with the said cam-block, and means for moving the latter inward and outward at predetermined times.
10. In an automatic circular knitting machine having a needle-cylinder provided with long, medium and short-butt needles, and instrumentalities, including main stitch cams and means for moving the cylinder in a rotary-reciprocatory manner, constructed, 15 arranged and adapted for coöperation for producing plain seamless stockings, the combination therewith of a radially movable secondary cam-block, a pair of oppositely facing knitting-cams, a pair of spaced apart 20 guard or wing-cams having the knitting-cams therebetween, a pair of independently movable auxiliary needle-elevating picks, said knitting-cams, wing-cams and auxiliary picks being movable bodily with the secondary 25 cam-block, means for moving said secondary cam-block toward and from the needle-cylinder, and means for positioning a secondary thread to be acted upon by the long-butt needles and members of said secondary cam-block when the latter is moved 30 inward toward the cylinder in the production of the split-foot part of a stocking.
11. In an automatic circular knitting machine for producing stockings having split 35 foot portions, the combination of a knitting cylinder and main knitting instrumentalities, including needles, knitting-cams, sinkers, and yarn-guides, arranged to convert a yarn into continuous courses of stitches, a 40 secondary cam-block, secondary stitch-cams fixed to said cam-block, a pair of auxiliary self-dropping picks pivoted to the cam-block for elevating the suture needles without knitting while the needle-cylinder is 45 moving in a reciprocatory manner, means for placing the yarns in and out of knitting position, and means for moving the secondary cam-block toward and from the needle-cylinder, for the purpose described.
- 50 12. In an automatic knitting machine of the general character described, provided with a revoluble needle-carrying cylinder, relatively stationary main stitch-cams and main narrowing picks, a secondary cam-block having stitch-cams, needle-deflecting 55 guard-cams, and swinging, needle-elevating auxiliary picks mounted thereon, said auxiliary picks arranged for operative engagement with certain of the needles of the cylinder, the last-named picks being located above the normal lower path of the needles, needle-depressing widening picks arranged in relation to the said auxiliary lifting picks, means for positioning said needle-depressing 60 picks, and means for moving said secondary cam-block toward and from the cylinder.
13. In an automatic knitting machine having a cylinder provided with needles and sinkers alternately, and means for moving the cylinder in a rotary-reciprocatory manner, the combination therewith of oppositely located inwardly facing main and secondary cam-blocks, each cam-block having stitch-cams, and guard-cams, means for feeding the main and secondary threads to the 65 needles and converting the threads into stitches through the medium of the said stitch-cams of the main and secondary cam-blocks, respectively, needle-elevating picks arranged with respect to the main stitch cams, auxiliary needle-elevating picks connected to and movable with the secondary cam-block, needle-depressing picks positioned contiguous to said auxiliary picks, and means connected with the secondary cam-block mechanism and with said secondary 70 yarn-changing devices for simultaneously positioning them for knitting action.
14. In an automatic knitting machine provided with a needle-carrying cylinder and coöperable instrumentalities for producing ordinary stockings, the combination therewith of a secondary cam-block, a plurality of 75 needle-actuating cams fixed to the inner concave face of the cam-block, a pair of swinging auxiliary needle-elevating picks having their inner free ends normally positioned, when in use, in the knitting path, so as to be 80 engaged by certain of the needles, means connected to the cam-block in producing the split-foot part of a stocking while the cylinder is moving in a rotary-reciprocatory manner, and means for moving the cam-block and its members 85 simultaneously to the normally idle, inoperative position.
15. In an automatic circular knitting machine having a needle-carrying knitting cylinder, a secondary cam-block, a plurality of 90 pairs of right and left needle-deflecting members fixed to the cam-block having inner concave faces and adapted, when in use, to lie contiguous to the outer face of the knitting cylinder, a pair of oppositely arranged 95 stitch-cams secured to the cam-block, the inner concave faces of the stitch-cams being depressed or recessed to permit certain of the needles to pass idly without knitting when the cam-block is positioned inward, a 100 pair of needle-elevating picks disposed with respect to the said stitch-cams, the inner ends of the picks extending beyond the face of the stitch-cams to receive the butts of certain other needles, and means for positioning the cam-block and the said needle-elevating members inward and outward.
16. In an automatic circular knitting-ma-

chine having a needle cylinder provided with long-butt, short-butt and suture needles and main knitting instrumentalities, a secondary cam-block, upper and lower center 5 guard-cams fixed to the cam-block, said guard-cams being vertically separated with their inner faces in vertical alinement, a pair of spaced apart stitch-cams having the guard-cams therebetween, said stitch-cams 10 also secured to the cam-block and arranged to form, when positioned inward, a space or clearance for passage of the short-butt and suture needles, a pair of independently controlled pivoted auxiliary picks arranged to be engaged by and elevate the suture needles, 15 said auxiliary picks being movable bodily with the cam-block, a pair of spaced apart outer wing or guide cams connected to and movable with the cam-block, and means for moving the cam-block and its members into 20 and out of knitting position.

In testimony whereof I have affixed my signature in presence of two witnesses.

GEORGE P. BOSWORTH.
